CHECK OUT COUNTER

Willie M. Shoffner, 2605 E. 3rd St., Dayton, Ohio

Filed Apr. 7, 1959, Ser. No. 55,400

Term of patent 14 years

(Cl. D80—2)

FIG-1

Fig. 1 is a front perspective view of a check out counter embodying my new design;

Fig. 2 is a rear perspective view thereof;

Fig. 3 is a top plan view thereof; and

Fig. 4 is an end elevational view taken from the right of Fig. 3.

I claim:

The ornamental design for a check out counter, substantially as shown.
